UNITED STATES PATENT OFFICE.

DAVID HENRY LOVELL, OF RENOVO, PENNSYLVANIA.

SPRING-FROG.

SPECIFICATION forming part of Letters Patent No. 338,177, dated March 16, 1886.

Application filed December 9, 1885. Serial No. 185,147. (No model.)

To all whom it may concern:

Be it known that I, DAVID HENRY LOVELL, of Renovo, in the county of Clinton and State of Pennsylvania, have invented a new and Improved Spring-Frog, of which the following is a full, clear, and exact description.

This invention relates to certain new and useful improvements in that class of railroad-frogs constructed with a spring-rail, which can be forced outwardly by the flange of the wheel of the passing locomotive or cars.

The object of my invention is to prevent the breaking of the spring-rail by badly-worn wheels.

The invention consists in the construction and arrangement of parts, as will be herein-after fully described and claimed.

Reference is to be had to the accompanying drawings, forming part of this specification, in which similar letters of reference indicate corresponding parts in all the figures.

Figure 1 is a plan view of my improved spring-frog. Fig. 2 is a side view of the same. Fig. 3 is a cross-sectional view on the line *x x*, Fig. 1. Fig. 4 is a cross-sectional view on the line *y y*, Fig. 1. Fig. 5 is a cross-sectional view on the line *z z*, Fig. 1. Fig. 6 is a cross-sectional view on the line *w w*, Fig. 1.

In my improved frog, A is the spring-rail, B the siding-rail, and C the main-track rail. P is the point of the frog. D is the wing and other siding rail.

The main-line rail C and the wing-rail D are of the ordinary height; but the tops of the siding-rail B and the spring-rail A are about one-fourth of an inch lower than the tops of said main-line and wing rails, and the point P is beveled lengthwise and laterally at its top from its pointed end, the said pointed end being as high as the spring-rail, as is shown in the section Fig. 5.

The total length of the spring-frog is usually about fifteen feet, the spring-rail part being usually about eleven feet long; but I do not limit myself to anything in the construction of the spring-frog, as it may be constructed of any suitable length, having a spiral, bow, rubber, or any other suitable spring acting on the movable rail, and the several parts forming the frog may be secured on or to a plate or directly on the sleepers or cross-ties

by any of the various methods of clamps or bolts.

My improvement can be applied on all kinds of frogs in use at present, all that is necessary being to reduce the height of the siding and spring rails, or the equivalent of the spring-rail, and to bevel the point P in the manner set forth.

The rails forming the frog may have any desired cross-section and any desired height and weight per foot; but in all cases the siding and spring rails must be lower than the other part.

The operation is as follows: A wheel with a badly-worn tire, as shown in dotted lines in Fig. 4, will, if the frog-rails are all of the same height, ride upon the main-track rail C until it comes in contact with the siding-rail B, when the outside or unworn part, *a*, of the tread mounts upon the rail B and rides upon it until it strikes the spring-rail A at the point *m*, and then it either mounts upon the spring-rail A, the whole bearing of the wheel then being upon an insecure and movable rail, and consequently increasing the liability of said rail to break, or, if the part *a* fails to mount the spring-rail at *m*, it forces it open or away from the siding-rail B and breaks it.

If the spring-rail A and the siding-rail B are lower than the main-line rail C, the bearing of the worn part of the wheel-tread will be where it should be—viz., upon the rail C—and the part *a* of the wheel will barely, if at all, touch the siding-rail B or the spring-rail A, at *m*, as the wheel readily runs from the higher main-track rail, C, to the lower spring-rail, A, the beveled point P making the change gradual.

I am aware that the upper bearing-surface of the siding rail leading to the frog has been cut away at its juncture with the main rail in lines parallel to said main rail, the remaining part of the siding rail being of the same height as the main rail, and I do not claim the same as of my invention.

Having thus described my invention, what I claim as new, and desire to secure by Letters Patent, is—

1. A railway spring-frog having the top of its spring-rail throughout its entire length a short distance below the top of the main-line

rail, substantially as herein shown and described.

2. The combination of the main rail C and the wing and siding rail D, of equal height, with the other siding-rail having its top surface lower than the top of the main rail C at its juncture therewith, and the spring-rail A, made lower throughout its entire length than the main and wing rails C and D, substantially as set forth.

3. A railway spring-frog having the top of the siding-rail and of the spring-rail a short distance below the top of the main-line rail and having the frog-point beveled, substantially as herein shown and described.

DAVID HENRY LOVELL.
